ERASING DEVICE

Charles Frederick, Columbiana, Ohio

Application August 17, 1937, Serial No. 159,590

8 Claims. (Cl. 120—36)

My invention relates to erasing devices.

Objects of the invention are to provide an implement comprising an erasing element of rubber or the like normally enclosed within a casing of metal or its equivalent and projectable therefrom into operative position. An important object of the invention is to provide means for closing or sealing the erasing element within the container when the erasing element is in its withdrawn or retracted position. In this way the rubber is kept clean and the device may be conveniently carried in the pocket, in a purse, a desk drawer or the like.

A further object is to incorporate in the casing means capable of ready and easy manipulation to project an operative end of the erasing element from an end of the casing and to hold or grip the extended end of the erasing element in exposed, operative position.

An additional object is to provide a structure of the class described, which may be very inexpensively made of strong, durable material and which will function efficiently throughout a long period of life, during which worn out erasing elements may be replaced by new ones.

Attempts have been made heretofore to encase rubber erasers in casings of metal or the like from which the erasing element may be projected for use and into which the element may be withdrawn between periods of use. In all of these prior art devices, so far as I am aware, there are inherent disadvantages. Notable among them is the failure of these devices to include closure means for the casing to protect the retracted rubber element from contamination by dust and dirt. Again, the best of the prior art devices with which I am acquainted is inconvenient to use because it is necessary for the fingers of the user to exert a compressive grip on the casing or the rubber element or both when the rubber is extended for erasing use. My present invention proposes an eraser casing having a closure for sealing the rubber or the like within the casing when the device is not in erasing use, and the invention also contemplates automatically gripping or holding the rubber in projected position by a simple preliminary movement of the parts, so that none of the user's attention or strength need be devoted to holding or gripping the rubber in extended position when an erasing operation is being performed.

The structure contemplated by the invention includes several novel constructional and manufacturing features which combine to produce an inexpensive and highly efficient article. These

advantages will be evident to persons skilled in the art from the following description of the principles of the invention as incorporated in a preferred form of embodiment.

In the drawing, which illustrates such preferred embodiment, which has been found to be entirely operative and practical, and is therefore at present preferred by me, although I recognize that the invention may be otherwise and differently embodied,

Figure 1 is a plan view of one face of the device with one of a plurality of erasing elements shown projected into operative position;

Fig. 2 is a plan view showing the opposite face of the device with the parts in the position shown in Fig. 1;

Fig. 3 is a side elevational view of the device in the position shown by Figs. 1 and 2;

Fig. 4 is a longitudinal sectional view taken on the line 4—4 of Fig. 2; and

Fig. 5 is a cross sectional view taken on the line 5—5 of Fig. 2.

Referring to the drawing, the device includes a casing 1, conveniently made of metal and preferably comprising a pair of interfitting channel portions 2 and 3. The proportions of the channels are such that the relatively narrow side flanges of the portion 2 are engaged within the somewhat wider side flanges of the portion 3, and the engaged pairs of flanges are secured together, preferably by electric welding, although other fastening means, as for example, rivets, pins or the like, may be employed.

The casing 1 is open at one end, if a single erasing element is to be built into it, or it may be and preferably is open at both ends, thus permitting the use of two erasing elements. The latter construction is preferred because, among other reasons, it permits the use of two different kinds of erasing elements, as for example rubbers of different characteristics, one capable of erasing pencil marks and the other capable of erasing ink marks, or an erasing element may be contained within one end portion of the casing and a brush or the like may be contained within the other end portion.

One face of the casing is slotted centrally as shown at 4. The slot preferably lies relatively near the open end of the casing. If both ends of the casing are left open, as has been explained above, a companion slot 5 is formed in the casing near its other end.

Slidably mounted within the casing is an eraser holding or backing means 6. This element may, for structural strength, be provided in the form

of a very shallow channel, preferably wide enough to make a snug fit with the casing interior. The rear or inner end of the slide 6 terminates in an outwardly directed neck 7, extending relatively 5 snugly through the slot 4 and terminating in a widened handle or manipulating element 8 which is wider than the slot and lies in a plane parallel 10 to that of the body of the slide 6. The arrangement is such that the tab or handle 8 is movable along and substantially in contact with the casing exterior adjacent to it. When the tab is moved toward the end of the casing, the end of the slide is projected through the opening at the end of the casing, and when the tab is moved 15 oppositely the slide becomes wholly contained within the casing.

The slide is adapted loosely to receive an eraser element 9 of rubber, rubber composition or other suitable material. The element 9 is made slightly 20 smaller in cross sectional shape than the casing space which receives it, so as to prevent binding of the rubber between the casing and slide parts. A tang or equivalent means 10 is struck up from the floor of the slide near its outer end portion. 25 The function of this tang or prong is to enter the rubber and move the eraser element out with the slide when the slide is projected. Obviously other means may be employed for this purpose, as for example a turned up rear end wall for the 30 slide, provided in the region of the neck 7.

The outer end of the slide or backing 6 is flanged upwardly as shown at 11. Preferably this flange forms an angle of the order of 45° with the slide floor, and it terminates at its upper end at 35 approximately the level of the upper casing wall, as shown in Figs. 3 and 4, so that when the erasing element 9 lies flat on the floor of the slide, as shown in dotted lines at the right of Fig. 3, the slide may be retracted within the casing, carrying the erasing element with it, and the flanged end 11 will form a closure for the otherwise open 40 end of the casing. In this way the retracted rubber is protected from contamination by dirt and the like when the eraser is not in use.

The angular disposition of the flange 11 permits the rubber 9 to be relatively withdrawn to a slight extent from the slide 6, when the slide is projected, and then the slide may be withdrawn 45 partially into the casing, while the end of the rubber remains relatively projected, so as to grip and compress the end portion of the rubber between the end of the casing and the flange. This disposition of the parts is shown at the left in Figs. 1, 2, 3 and 4. The movements preparatory to this disposition are illustrated in dotted lines 50 at the right in Figs. 3 and 4. Referring to these figures, the retracted position of the parts is shown in full lines in Fig. 4. From this position the slide and erasing element are projected together, as shown at the right of Fig. 3. The erasing element is then projected slightly beyond the outer end of the slide, as shown in dotted lines 55 in Fig. 4. The slide is then retracted into the casing as far as possible, whereupon the extended end of the erasing element becomes jammed or gripped in the casing opening, as shown at the left in Figs. 1, 2, 3 and 4, and the erasing operation 60 may be conducted with great facility and convenience.

The eraser is restored and the device closed by the reverse of the foregoing movements. The slide is first projected to release the grip on the rubber, the rubber is then pushed inwardly into the casing while the slide remains projected, and the slide and rubber are then moved inwardly to 70

gether into the casing. In this latter movement prongs or the like 12, struck up from the inclined flange 11, may be used to engage the end of the rubber and push the rubber along with the slide.

The operations thus described are the same for 5 both ends of the device if an eraser and slide be provided at each end.

With reference to the angular flange 11, it is pointed out that a preferred embodiment comprises forming slide side walls 13 on the flange. 10 These side walls help to guide and fix the line of the projected eraser element 9. They also strengthen the flange. If desired, they may be proportioned so as to intersect the plane of the upper face of the casing, in which event short 15 slots 14 may be provided in this face of the casing to receive the end walls 13.

As has been stated, it is recognized that the invention may be embodied in other and further modified forms. All such modifications, to the 20 extent that they incorporate the principles of the invention as defined by the appended claims, are to be deemed within the scope and purview thereof.

I claim:

1. An erasing device comprising a casing open at an end and having a slot formed in one of its sides, an eraser holder slidably in the casing having a handle portion extended through the slot, and a flange formed on the outer end of the holder adapted to close the end opening of the casing when the slide is retracted within the casing. 30

2. An erasing device comprising a casing open at an end and having a slot formed in one of its sides, an eraser holder slidably in the casing having a handle portion extended through the slot, and a flange formed on the outer end of the holder adapted to close the end opening of the casing when the slide is retracted within the casing and adapted to compress an extended end 40 portion of an eraser against said end of the casing when the eraser is extended from the holder and the holder is extended from the casing. 35

3. An erasing device comprising a casing open at an end, a backing for an eraser slidably mounted within the casing and having a flanged end normally closing the casing opening and sealing the eraser in the casing, and means for extending the eraser and its backing through the casing opening and holding the end portion of the 50 eraser extended in operative position from the casing.

4. An erasing device comprising a casing open at an end, a backing for the eraser slidably mounted within the casing and having a flanged end normally closing the casing opening and sealing the eraser in the casing, the eraser and backing being movable with respect to each other, and means for extending the backing through the casing opening with the eraser extended from 60 the backing and compressed between the backing flange and the end of the casing. 55

5. An erasing device comprising a casing open at an end, a backing for the eraser slidably mounted within the casing and having a flanged end normally closing the casing opening and sealing the eraser in the casing, and means for projecting the backing and the eraser as a unit through the end opening of the casing, the projected end portion of the eraser being detachable from the backing and adapted to be extended beyond the backing for compression between the casing and the flanged end of the backing. 65

6. An erasing device comprising a casing open at an end, a backing for the eraser slidably 70

75

30

40

mounted within the casing and having an operating element extending through a slot in the casing, a flanged end formed on the backing normally closing the casing opening and sealing the
5 eraser in the casing, and means carried by the backing and engaged with the eraser for moving the eraser with the backing when the backing is projected through the end opening in the casing, said means being disengageable from the eraser
10 whereby the eraser may be extended beyond the projected backing and compressed in operative position between the adjacent ends of the backing and casing.

7. An erasing device comprising a casing open
15 at an end, a backing for an eraser slidably mounted within the casing, a flanged end formed on the backing normally closing the casing opening and sealing the eraser in the casing, and means carried by the backing and engaged with the
20 eraser for moving the eraser with the backing when the backing is projected through the end opening in the casing, said means being disen-

gageable from the eraser whereby the eraser may be extended beyond the projected backing and compressed in operative position between the adjacent ends of the backing and casing.

8. An erasing device comprising a casing open 5
at an end, a backing for an eraser slidably mounted within the casing, a flanged end formed on the backing normally closing the casing opening and sealing the eraser in the casing, means 10 carried by the backing and engaged with the eraser for moving the eraser with the backing when the backing is projected through the end opening in the casing, said means being disengageable from the eraser whereby an end portion 15 of the eraser may be extended beyond the projected backing and compressed in operative position between the adjacent ends of the backing and casing, and a projection formed on the backing engageable with said end portion of the eraser for moving the eraser with the backing when the 20 backing is returned into the casing.

CHARLES FREDERICK.

CERTIFICATE OF CORRECTION.

Patent No. 2,115,806.

May 3, 1938.

CHARLES FREDERICK.

It is hereby certified that error appears in the printed specification of the above numbered patent requiring correction as follows: Page 2, second column, lines 54, 64, and 75, claims 4, 5, and 6 respectively, for "the" read an; and that the said Letters Patent should be read with this correction therein that the same may conform to the record of the case in the Patent Office.

Signed and sealed this 14th day of June, A. D. 1938.

(Seal)

Henry Van Arsdale,
Acting Commissioner of Patents.
